HEAT MOVER

Milton A. Powers, Detroit, Mich.

Application July 30, 1946, Serial No. 687,172

7 Claims. (Cl. 98—39)

1

This invention relates to apparatus for circulating and redistributing air within a confined space such as that afforded by one or more rooms of a house.

More specifically, the present invention is primarily concerned with an attempt towards equalization of temperatures within the living quarters of a house heated in such manner that the normal tendency is for most of the warmed air to rise to the ceiling zone. Practically all heating systems are such that the ceiling zone must be overheated to obtain comfortable temperatures at lower levels, and in many cases it is impossible to attain an adequate temperature at any level adjacent the floor.

For example, in small homes having no basement and therefore no heating plant below the house, it is impossible to maintain a safe temperature at the floor, and this is particularly true of houses wherein only one room contains a heating unit. Moreover, in the latter type of house, heat is localized around the heating unit and concentrated at the ceiling thereabove. It has been proposed to use fans to remedy this condition, but the usual tendency has been to create undesirable drafts without sufficient equalization of temperatures.

It is the primary object of the present invention to devise a simple heat mover and mount it in such manner that the air within one or more rooms can be circulated and redistributed adequately to provide comfortable and healthful temperature conditions. In this connection it is an important object to properly locate an electric fan unit within the house and to design it for convenient and substantially universal adjustment.

Another major object of my invention resides in the provision of a heat mover of the character above mentioned which is light, compact and inexpensive, and which has an almost negligible power requirement.

It is an object of this invention to mount an air circulator upon a door jamb or a window casement, and to devise a clamping means for adjustably supporting the circulator in such position.

A further object is to construct a circulating apparatus from a roughly L-shaped and adjustable supporting bracket and an electric fan mounted upon one end of said bracket. In this connection further objects are to make the bracket in detachable sections for compact packaging and storage and for easy dismounting and reassembly; and to make the bracket hollow so

2

that it may at least partially house an elongated electric cord.

It is another major object to devise a new and improved mounting for supporting an electric motor casing; and it is also an object to utilize the mounting for support of a fan blade guard in novel manner.

The foregoing and additional objects of the present invention should become fully apparent from a study of the following description when taken in conjunction with the accompanying drawings, wherein:

Fig. 1 is a face view of a preferred embodiment of the invention, shown attached to a door or window frame in one position of adjustment.

Fig. 2 is an enlarged side elevational view of the fan assembly of Fig. 1, broken away from its supporting bracket.

Fig. 3 represents an enlarged section taken substantially upon the plane of line 3—3, Fig. 1.

Fig. 4 is a fragmentary view similar to Fig. 1 but showing the supporting bracket swung to another position and the fan unit oscillated relative to the bracket.

Fig. 5 represents an enlarged detail view of the supporting clamp in section, taken along the plane of line 5—5, Fig. 1.

Fig. 6 shows a portion of an arrangement of a plurality of rooms, one of which contains a space heater and wherein my circulating unit is mounted to force warm air into an unheated room.

With continued reference to the drawings, the numeral 7 designates a rectangular frame that may be either a door jamb or a window casement. To one vertical side member of this frame there is secured by four wood screws 10, a clamp consisting of a pair of L-shaped brackets 8 which have vertically aligned circular apertures 9 and which are spaced apart to receive a sleeve 11.

The latter is integral with the brackets or may be rigidly attached thereto, as by welding. The sleeve 11 carries a manually operable set screw 12 cooperable with a straight rod or pipe 13 that passes freely through the aligned apertures 9. By loosening the set screw, the pipe may be oscillated and/or vertically adjusted.

The pipe 13 forms one section of a two-part stanchion which, as presently seen, supports an electric fan. The second section comprises a vertical pipe 14 rigidly joined to the pipe 13 by a coupler 15 and bent near its upper end to provide a horizontal extension 16. Just above the coupler 15 the pipe 14 has an eyelet or bushing 17 through which are passed the wires 18 of an electric cord designed to be connected in con-

ventional manner to any convenient electrical outlet. The wires 18 extend through and beyond the pipe elements 14, 16 for connection to an electric motor. The wires obviously could be entered into and passed through the pipe 13, and such would be done if the pipes 13 and 14 were formed in one piece but, for convenience of assembling and disassembling the entire bracket (which preferably is made in two parts for compact packaging and to facilitate movement from one clamp to another) the wires pass only through the pipe 14. It follows that the member 13 could be formed as a solid rod.

The motor mounting per se comprises a U-shaped device 20 which has a base 21 through which the outer end of pipe 16 freely projects, and which has two parallel sides 22 terminating in a pair of narrow arms 23. The extremities of these arms are cylindrically curved and attached, as by screws 24 or any other suitable means, to a semi-cylindrical band 25 that straddles a motor casing 26. The casing has three recesses 27, equally spaced circumferentially and facing the band 25 which, as shown, has three complementary apertures. A flanged pin or button 28, of soft rubber or the like is fitted tightly between each recess and its complementary aperture to afford a noiseless and vibration-absorbing clamp for the motor and its fan blades 29. The ends of the band 25 are sufficiently resilient to permit them to be sprung outwardly for insertion and removal of the motor.

The average size of the fan, for home use is about eight inches (diameter), and its motor has a capacity of only about $1/250$ horsepower. The entire dismantled apparatus may be packed for shipment in a box about 10 x 8 x 24 inches. A model of this size has been built and very effectively operated.

One of the wires 18 is connected directly to the motor and the other passes first through a switch 30 that is secured to the mounting base 21 by a sleeve nut 31. A pull chain 32 is connected to the switch 30 to control the motor.

The plates 22 are wide enough to provide a pair of integral wings 33 in offset relation to the arms 23. These wings are cylindrically curved with respect to the fan axis and are secured by screws or other suitable means to a correspondingly curved guard ring 34. This ring surrounds the fan blades and its entrance side is flared outwardly, as shown, to cause a greater and smoother flow of air than would be obtainable otherwise. If desired, a detachable grill in the shape of a disc may be fitted to the flared entrance rim, this being advisable when the apparatus is mounted as in Fig. 6.

The fan unit is stabilized relative to the pipe element 16 by fitting a small U-member 35 between the arms 23, to which it may be rigidly secured by welding. The base of member 35 is apertured to permit the pipe 16 to project freely therethrough, and an end cap 36 is secured to the pipe to keep the fan unit from falling off. A ring 37 may be added, by welded or screw threaded attachment, to prevent the fan unit from sliding towards the pipe section 14.

It will be perceived that the entire fan and its mounting assembly is oscillatable around the horizontal pipe 16. To prevent this oscillation or, rather, to lock the assembly in any desired position of angular adjustment, a manually operable set screw 38 is carried by one of the plates 22 for engagement with the pipe.

In Fig. 1, the two adjustments (12, 38) are

such that the fan is disposed within the upper part of a doorway or window and blowing a current of air transversely therethrough. In the case of a doorway the air is being passed from one room to another as, for example, from a heated living room to a cold bathroom or bedroom. If the frame 7 is a window casement, either warm and smoky air is being expelled or fresh air from the atmosphere is being indrawn. The fan of course may be tilted slightly and/or swung about the axis of pipe 13 to redirect the air stream.

In Fig. 4, the fan has been swung entirely away from the door or window frame 40, and it is forcing air directly downward from the ceiling. It may be oscillated 180 degrees to blow upwardly, or to any intermediate position. In all situations it of course may also be raised or lowered through the sleeve 11.

Fig. 6 illustrates part of an arrangement of a plurality of rooms having a common floor level, wherein one of the rooms, 42—usually the living room—contains a heater 43 mounted at floor level, the other rooms containing no permanently fixed heating appliances. My heat mover is mounted upon the door frame 40 and adjusted to withdraw hot air from the upper part of the room 42 and to force it into an adjacent room 44. It should be understood that the door to room 44 normally is closed, and that the heat mover normally is adjusted to obtain a substantially uniform temperature at all levels within the room 42, as explained below.

When operating to circulate air in the living room only, experience has shown that the fan is fully effective in maintaining a substantially even temperature throughout the room regardless of the direction in which the fan is pointed. However it has been found that most satisfactory results are obtained, and there are no noticeable drafts at the living level, if the fan is directed somewhat toward and across the ceiling.

A living room heated with a conventional stove or space heater may show a temperature of as much as 90 degrees at the ceiling and as low as 55 degrees at the floor level in extreme cases while the temperature is 70 degrees at a level about five feet up from the floor, but after my heat mover has been in operation a short time such variations in temperatures are substantially eliminated. This is due to the fact that there is a continuous and steady displacement of the heated air from the ceiling which flows downward slowly to replace the cooler air near the floor which in turn is moved upward through the fan and displaced across the ceiling. The warmer air against the cold floor serves to warm it and thus to reduce the hazard to health which is so commonplace in basementless homes where babies and children are forced to play upon the living room floor.

Thus, in a living room equipped with my heat mover a desired temperature of, say, 72 degrees may be obtained at the five foot level, and there will be at the same time a variation of not over two or three degrees in any area of the room except, of course, directly over the heating unit itself. Thus, in addition to saving a considerable portion of the fuel otherwise expended in uselessly heating the ceiling, the comfort conditions throughout the room are immeasurably increased.

In addition to its value in maintaining even temperature in the living room my heat mover

has been designed to effectively accomplish an entirely different objective by means of a quick and easy adjustment. In most small homes heat is only available from the heater located in the living room, and very little if any heat from it flows to the adjoining rooms, unless the living room is extremely overheated, and even then the results are poor.

However, as explained earlier, the clamping arrangement allows the fan member to be readily swung over the register with the adjoining upper corner opening of the doorway leading to the other rooms. When so located the fan is entirely up out of the way and in no way obstructs use of the doorway in normal manner. At the same time, however, warm air from the living room passes through the fan and is forcefully directed into the adjoining bedroom, the bathroom, or the hallway leading to such rooms. Under these circumstances such rooms receive substantial amounts of heat; and, as this heated air is driven by mechanical means, it quickly and effectively permeates all portions of the room.

Obviously, for every cubic foot of warm air removed from the living room another cubic foot must return from the adjoining rooms, and such as the case. This returning air flows across the floor back to the living room where it returns to the base of the heater and is warmed. Thus, without the necessity for any ductwork whatever, we have in substance a forced warm air heating system which is extremely effective in operation and simple in construction and low in cost. Furthermore, it can be installed in any small home without any necessity for structural change; its installation does not occupy any usable space whatever; and its alternate use for maintaining even temperature in the living room makes it an extremely desirable adjunct to most small homes.

It is desirable to have two or more clamp units secured to various doors and windows so that the circulating apparatus can be moved about the house and mounted quickly in any selected position. Also, obviously, two or more pieces of apparatus may be utilized simultaneously as a battery in a single group of rooms.

It should be understood that numerous changes in construction may be made within the spirit and scope of this invention, and that I wish to be limited in customary manner only by a reasonably liberal interpretation of the appended claims.

What is claimed is:

1. In a mounting device for an electric fan, an approximately semi-cylindrical yoke carrying three pins radially arranged and disposed approximately 90 degrees apart, a motor casing fitted within said yoke in spaced relationship thereto and connected to said pins, the ends of said yoke being sufficiently resilient to permit convenient insertion and removal of the motor casing.

2. In the device set forth in claim 1, said pins comprising a cushioning material such as soft rubber.

3. In an apparatus of the class described, an elongated supporting element, a U-shaped member having an apertured base pierced by said element and a pair of arms extended along opposite sides of the latter, a cradle provided at the ends of said arms and an electric fan carried by said cradle, a bridge secured across said arms, said bridge having an aperture pierced by said element, whereby the fan and said member are oscillatable as a unit about said element, and

means for locking the unit in position against oscillation.

4. In the apparatus defined in claim 3, said element being hollow, and there being an electric cord housed thereby and connected to said electric fan.

5. In combination, a U-shaped bracket having its sides split longitudinally to form a pair of parallel arms and an offset pair of divergent arms, a cradle secured to the ends of said parallel arms, a rotary fan carried by said cradle, and a fan guard unit having a circular rim secured to said divergent arms so that its axis is coincident with that of said rotary fan.

10 6. In an apparatus of the character described, a stanchion comprising an upright elongated member having a substantially horizontal extension at one end, mounting means receiving said upright member with capacity for vertical

20 and rotational adjustments of the latter, an electric fan disposed adjacent the free end of said extension with its axis transverse to but within a plane containing the axis of said extension, and a device for mounting said fan in the position

25 just described, said device comprising a cradle for the fan motor having an elongated element directly projecting laterally from the motor and telescopically received by said free end of the extension and having adjustment means

30 readily permitting oscillation of said cradle relative to said free end.

7. In a small home unit comprising at least a primary room and an adjoined room at substantially the same floor level and interconnected

35 by the usual doorway, a heater mounted within and designed to discharge its entire useful heat output at a low level into said primary room, a stanchion mounted upon a jamb of said doorway for both vertical and oscillational adjustment

40 and having a substantially horizontal arm at its upper end that may project into said primary room or extend across the top of the space defined by said doorway, and a dustless electric fan having means mounting it upon the free end of

45 said arm with its axis transverse to and within a plane of the arm's axis, said mounting means including a manipulative device for universally adjusting said fan to a multiplicity of positions with respect to said arm, whereby the fan may

50 be positioned to circulate air in substantially any of all directions across the interior of said primary room, or, to distribute heated air through space from the upper portion of said primary room into the adjoined room by way of said doorway.
